UNITED STATES PATENT OFFICE.

ALFRED A. FISK, OF POMONA, CALIFORNIA, ASSIGNOR OF ONE-HALF TO A. B. DAVIS,
OF POMONA, CALIFORNIA.

DOOR-LATCH AND BURGLAR-ALARM.

1,353,388.

Specification of Letters Patent. Patented Sept. 21, 1920.

Application filed September 23, 1918. Serial No. 255,305.

To all whom it may concern:

Be it known that I, ALFRED A. FISK, a citizen of the United States, residing at Pomona, in the county of Los Angeles and 5 State of California, have invented a new and useful Door-Latch and Burglar-Alarm, of which the following is a specification.

The subject of this invention is a door latch intended to be temporarily placed in 10 position to prevent a door being opened.

The main object of the invention is the provision of a latch with means for attaching the same to a door jamb.

Another object of the invention is the 15 vision of an audible signal on the latch.

The invention also contemplates generally improving the construction and enhancing the utility of door latches.

With the foregoing and other objects in 20 view, which will appear as the description proceeds, the invention resides in the combination and arrangement of parts and in the details of construction hereinafter described and claimed, it being understood that 25 changes in the precise embodiment of the invention herein disclosed can be made within the scope of what is claimed without departing from the spirit of the invention.

A practical embodiment of the invention is 30 shown in the accompanying drawing, wherein:

Figure 1 is a plan view of the device, a fragment of the door to which it is applied being shown in section;

35 Fig. 2 is a view in front elevation of the same, the bell being removed;

Fig. 3 is a central longitudinal section of the device, the bell removed;

Fig. 4 is a view in side elevation of the 40 device, shown in open position with the bell indicated in dotted lines.

Referring to the drawing by numerals of reference:

In carrying out the invention there is provided a plate, 1, preferably formed of thin metal, and to this plate are riveted or otherwise secured the spurs, 2, and the positioning lug, 3.

Pivottally secured by a pin, 4, or otherwise

to one end of the plate, 1, is a tongue, 5, the free end of which is bent to form an extending stop, 6. A boss, 7, is riveted or otherwise secured to the plate, 1, and serves to enter a depression, 8, formed in the tongue, 5, when the tongue is swung to a position 55 overlying the plate, thereby retaining the tongue against displacement.

The stop, 6, is provided with apertures, 9, to permit the passage therethrough of the push rod, 10, which extends from and is 60 operatively connected with a bell, 12, which bell is suitably secured on the tongue, 5.

In practice, the tongue, 5, is swung to open position, as shown in dotted lines in Fig. 1, and also shown in full lines in Fig. 4, 65 and the end of the plate, 1, to which the spurs are attached, is placed against the door jamb, 9, with the spurs, 2, in position to contact the jamb, and the positioning lug, 3, in position to rest against the face of the 70 jamb.

With the parts in this position, the door, 11, is swung to closed position, thereby contacting the plate, 1, and forcing the spurs, 2, into the wood of the jamb and anchoring the 75 plate, 1, firmly in place. The tongue, 5, is then swung to closed position, as shown in Fig. 1, bringing the stop, 6, into position to be contacted by the door, when the door is swung slightly opened, and restrain the door 80 from further opening, and also in such position that the end of the push rod, 10, will be contacted by the door to operate the bell, 12, and sound an alarm.

Having thus described the invention, what 85 is claimed as new and sought by Letters Patent, is:

The combination with an elongated metal plate having a bowed end portion for insertion between a door and a jamb, and a jamb 90 engaging spur extending from said end portion, of a tongue pivotally mounted upon the other end portion of the plate and having its free end folded and constituting an angular stop movable to position in the path of the 95 door, an alarm mounted on the tongue, a plunger slidably mounted in and guided by the stop for actuating the alarm, one end of

the plunger being movable to position in contact with the door to sound the alarm when the door is shifted against the stop, and coöperating means upon the plate and tongue 5 for holding said tongue with the stop in door fastening position.

In testimony that I claim the foregoing as

my own, I have hereto affixed my signature in the presence of two witnesses.

ALFRED A. FISK.

Witnesses:

W. M. LATINE,
JEAN C. WOOD.

It is hereby certified that the name of the assignee in Letters Patent No. 1,353,388, granted September 21, 1920, upon the application of Alfred A. Fisk, of Pomona, California, for an improvement in "Door-Latches and Burglar- Alarms," was erroneously written and printed as "A. B. Davis," whereas said name should have been written and printed as *A. B. Avis*, as shown by the records of assignments in this office; and that the said Letters Patent should be read with this correction therein that the same may conform to the record of the case in the Patent Office.

Signed and sealed this 30th day of November, A. D., 1920.

[SEAL.]

L. B. MANN,

Acting Commissioner of Patents.
